DESIGN FOR A FIRE-PLACE.

Design No. 13,445, dated November 21, 1882.

UNITED STATES PATENT OFFICE.

WILLIAM C. PEET, OF JERSEY CITY, NEW JERSEY, ASSIGNOR TO THE J. L. MOTT IRON WORKS, OF NEW YORK, N. Y.

DESIGN FOR A FIRE-PLACE.

SPECIFICATION forming part of Design No. 13,445, dated November 21, 1882.

Application filed October 17, 1882. Term of patent 7 years.

To all whom it may concern:

Be it known that I, WILLIAM C. PEET, of Jersey City, in the State of New Jersey, have invented a certain new and ornamental Design 5 for Fire-Places, of which the following is a specification.

My design is shown in the annexed engraving.

In this design the fire-place, the frame, and 10 the fender are all made with reference to the production of a peculiar artistic effect which results from the plain parallel lines with ornaments at the angles and ends of the parts. The fender-frame has posts *a*, base-bars *b*, 15 and rails *c*, ornamented with the conical ornaments *d* at the tops and the circular leaflet rosettes *e f* at the junction of some of the posts and base-bar. The fire-place frame *s* is plain, with beveled edges, and rosette ornaments *f'* 20 at the angles. The fire-place is composed of bars *h*, ornamented with urn-shaped ends *k*, and the front supports are prismatic with vase-shaped ornaments *l* at the top, round beads

and covers *n* at the bottom, and curved legs *o*. These ornamental parts on the fender, fire- 25 place, and frame compose as a whole a plain unique design.

I claim as my invention—

1. The design of the fender, consisting of the posts, rails, and bars ornamented with the 30 conical heads *d* to the posts and the circular-rosette ornaments, substantially as represented.

2. The design of the fire-place frame, having beveled edges and circular-rosette ornaments, substantially as represented. 35

3. The design of the fire-place, composed of the bars *h*, with urn-shaped end ornaments, the prismatic supports and vase ornaments *l*, and curved legs, substantially as represented. 40

Signed by me this 13th day of October, A. D. 1882.

WILLIAM C. PEET.
